VARIABLE STROKE PUMP

William H. Swartz and Charles G. Swartz, York,
Pa., assignors to General Machine Works, Inc.,
York, Pa., a corporation of Pennsylvania

Application August 29, 1931, Serial No. 560,196

1 Claim. (Cl. 103—38)

The invention relates to machines by means of which grease, liquid, paste, granulated materials or the like are applied or distributed and has for its general object the provision of means for automatically delivering any given quantity of grease or other materials to the distributing means at any regular or irregular intervals, it being a feature that the deliveries can be pre-arranged by various adjustments:

10. While the invention is susceptible of employment in connection with various types of apparatus, it applies more particularly to machinery for greasing or otherwise coating containers or pans used specially in bakeries where bread, cakes, pies and the like are produced in large quantities.

15. A very important object of the invention is to provide an attachment of this character, wherein in its operation the same effects control of the feed or distribution of the grease or other material to the pans or anything else to be coated.

20. A further object of the invention is to provide an attachment of this character, wherein there is embodied pump means for supplying grease or the like to swabs or other greasing elements, the attachment being susceptible of a variable stroke so that a predetermined quantity of grease or other substance may be fed.

25. A still further object is to provide an attachment of this character in which there is a positive and definite control means for regulating the feed of grease or the like to the distributing means, this control means being moreover of such form and arrangement as to be capable of having applied thereto graduations or visible indicia whereby any desired adjustments may be brought about to insure the proper rate of feed of material to the distributing means.

30. An additional object is to provide a mechanism or attachment of this character which will be comparatively simple and inexpensive to manufacture, easy to control, positive in action, efficient and durable in service, and a general improvement in the art.

35. With the above and other objects and advantages in view, the invention preferably consists in the arrangement and combination of parts and the details of construction to be hereinafter more fully described and claimed, and illustrated in the accompanying drawings, in which:

40. Figure 1 is a side elevation of a pan greasing machine embodying our invention, part being broken away.

45. Figure 2 is an end elevation.

Figure 3 is a vertical cross sectional view taken on substantially the line 4—4 of Figure 1.

Figure 4 is a vertical detail sectional view taken through one of the distributors.

Figure 5 is a fragmentary view partly in elevation and partly in section showing one of the mechanical features involved in the invention.

Figure 6 is a detail horizontal section showing a plan view of the lever or arm for rendering the grease feeding mechanism temporarily ineffective.

Figure 7 is a detail cross section taken on the line 8—8 of Figure 6.

Referring more particularly to the drawings we have shown a machine for greasing pans of any desired size or shape, this machine comprising a frame indicated generally by the numeral 10 and comprising any necessary number of legs 11 to which are secured upper and lower longitudinally extending angle bars 12 and 13 and transversely extending angle bars 14 and 15, all the various bars being secured together in any preferred manner. Obviously it should be distinctly understood that there is nothing particularly distinctive or unusual about the frame as the construction thereof might be varied within wide limits, the disclosure being simply for purposes of illustration. Mounted within the frame 10 and extending longitudinally of the upper portion thereof are shafts or rods 16 and 18 on which are mounted carriages 19 arranged in spaced relation and adapted to be moved and held in adjusted position by a screw 17 extending through threaded bores in the carriages 19.

25. Secured upon each of the carriages 19 is a retaining bracket structure 21 of angular form held in place in any desired manner as for example by means of cap screws 22 or the like. Journalled within each of the carriages 19 is a tubular spindle 23 extending through bearing portions 24 in the brackets 21. Each of these tubular or hollow spindles 23 is formed with a pinion 25 and all of the pinions are in mesh with a rack bar 26 slidably mounted for sliding movement within all of the brackets 21 and adapted to be moved longitudinally for the purpose of effecting rotation of the spindles 23.

30. Located above and in axial relation to the hollow or tubular spindles 23 are other tubular spindles 27 each of which is formed with an annular groove 28, the spindles 27 being connected with the spindles 23 by collars 29 which embrace both and overlap the joints between them, the collars being secured to the spindles 23 as by set screws 30 and being 35.

secured with respect to the spindles 21 as by other set screws 31 carried by the collars 29 and engaging within the annular grooves 28. At its upper end, each spindle 21 is provided with a 5 carrier 32 having upstanding pins or the like 33 constituting a grip or clutch for holding a swab, brush or the like 34 preferably of somewhat tapered or conical form. The respective swabs 34 are intended to engage within the pans 35 to be 10 greased or otherwise treated or coated. Logically the swabs or brushes 34 must have interiorly located ducts communicating with the hollow spindles 21 for the purpose of conducting grease, oil or in fact any other desired substance into 15 and through the swabs so that the material will be applied to the pans 35 in the form of a coating.

Mounted at the top of the frame 10 is a tray-like casing or guard 36 within which is a pan 20 support 36a and having a bottom wall 37 located beneath all of the brushes or swabs 34 and provided for the purpose of preventing the grease or other material from being thrown out and onto surrounding objects, it being a feature that 25 any desired drain means whatsoever, not shown, may be provided for the purpose of conducting back into the supply source the surplus grease or other material distributed onto the pans 35 by the swabs or brushes 34. Of course when the 30 rack bar 26 is moved longitudinally the spindles 23 and 27 will be rotated as will also be the swabs or brushes 34.

Located beneath the shaft or rod 16 and supported therefrom or supported in any other desired manner is a shaft 38 carrying any desired 35 number of crank arms 39 connected by a link 40 with a longitudinally extending shaft 41 which extends throughout the length of a longitudinally extending trough or hopper 42 adapted to contain 40 grease, oil or in fact any other substance to be applied to the pans 35 or any other analogous articles or objects. The trough or hopper 42 is carried by one or more members 43 on the upper end or ends of one or more plungers 44 urged upwardly by a spring or springs 45. Within 45 the hopper or trough 42 each spindle 23 is surrounded by a sleeve 46 which acts as a cylinder with the hollow spindle serving as a piston. Any suitable pump and valve means may be provided, not shown, so that the grease or other 50 substance will be caused to enter the cylinders 46 and pass from them into and through the spindles 23 and 27 to and through the swabs or brushes 34.

55 The means for controlling the feed or supply of grease or other substance to the pans or other objects to be treated is herein disclosed as comprising a constantly driven shaft 49 which might be the main shaft of the machine or which may be driven by an electric motor or in fact any other type of power device. This shaft 49 carries a pinion 50 meshing with an intermediate gear 51 suitably journaled and carrying a pinion 52 meshing with a relatively large gear 53 suitably 60 journaled on a bracket structure 54 mounted at the intermediate portion of the frame 10. The gear 53 is shown as formed with a plurality of spaced projections 55 upon a selected one of 65 which is secured as by a single screw 55a a cam 56. Cooperating with the cam 56 is an angle lever 57 pivoted intermediate its ends on a suitable bracket as shown at 58 and provided at one end with a roller 59 adapted to be engaged periodically by the cam 56. The other end of the lever 70

57 is formed with an eye 60 having its interior of toroidal shape as clearly illustrated in Figure 7 and receiving a pin 61 projecting from one end of a rocking lever 62 which is pivoted intermediate its ends as shown at 63 and which has its other end formed with an eye 64 slidably engaged upon a vertically arranged rod 65 having a threaded connection 66 at its upper end within a socket 67 pivotally connected at 68 within a clevis 69 on one end of a crank arm 70 on the end 10 of the shaft 38. The vertical rod 65 carries a stop collar 71 against which the free end of the rocking lever 62 engages, and beneath and abutting against the free end of the lever 62, or against the eye 64 at the end thereof, is a spring 72 which 15 in turn abuts against an additional collar 73 secured on the rod 65. Clearly, when the rocking lever 62 is oscillated about its pivot 63 the cooperation or engagement of the eye 64 with the collar 71 will cause vertical reciprocating movement of 20 the rod 65 and socket 67 and consequent rocking movement of the crank arm 70 and rock shaft 38, and as the latter is connected by the crank arm or arms 39 with the link or links 40 carrying the cylinders 46 the cylinders are moved with respect 25 to the pistons therein for effecting the pumping action and in this way the quantity of material fed through the hollow spindles 23 and 27 to the swabs or brushes 34 may be regulated.

Cooperating with the lower end of the vertical 30 rod 65 is means for limiting its downward movement, this means being here disclosed as comprising a quadrant 74 eccentrically pivoted as shown at 75 and formed in its periphery with a plurality of notches 76 adjacent which there may 35 be provided graduations or indicia of any sort desired for giving the operator a clear reading as to the position and length of movement or travel of the rod 65 and consequently the pump stroke. The quadrant 74 is of course pivotally mounted 40 and it is intended that its position be altered to bring about the desired results, and for this reason we have shown and integrally formed wing nut or hand-piece 77 by means of which it may be quickly and easily turned without any necessity for the employment of tools. The lower end of the rod 65 is rounded and may be engaged within a selected one of the notches 76 in the circumference or periphery of the eccentric quadrant 74. 50

Clearly, when the main shaft 49 is rotating the reducing gears 50, 51, 52 and 53 will be driven and the cam 56 will periodically engage the roller 59 and rock the angle lever 57 periodically so that the rocking lever 62 will be correspondingly rocked or moved in an oscillatory manner upon its pivot 63 so that the eye 64 cooperating with the stop collar 71 on the rod 65 will cause the latter to move vertically, resulting in rocking movement of the crank arm 70, shaft 38, and crank arm 39 for varying the stroke of the pump mechanism. 55

Obviously, by rotating the eccentrically mounted quadrant 74 the distance between its pivot and the successive notches or depressions 76 may be varied so that the extent of movement of the rod 65 and consequently the pump stroke may be varied. 65

Another important feature of the invention resides in the provision of means for rendering the entire pumping mechanism ineffective temporarily in case it is necessary for the operator to leave the machine for a short length of time. In accomplishing this, we provide a rock shaft 81 70

which is vertically arranged and journaled in suitable brackets carried by the frame, one bracket having spaced lugs indicated by the numeral 82. At its upper portion this rock shaft 5 carries a handle 83 by means of which it may be partially turned, and at its lower portion it carries an arm 84, more clearly disclosed in Figure 6, having a hub portion 85 fitting fairly closely between the lugs 82. This arm is adapted to be 10 rotated partially so as to interpose it between the lower end of the vertical rod 65 and the notches in the periphery of the quadrant 74. For this reason it is preferable that the arm 84 be wedge shaped in cross section as shown in Figure 7 so 15 that when the rod 65 is in its elevated position the operator may by grasping and moving the hand lever 83 partially rotate the shaft 81 to force the thin edge of the arm 84 between the lower end of the vertical rod 65 and the quadrant 20 74 so that there will be nothing to move the shaft 65 up and down under these circumstances. This will mean that the pump mechanism is temporarily idle so that no grease or any other substance will be fed to the distributing swabs or 25 brushes 34.

From the foregoing description and a study of the drawings it will be apparent that we have thus provided a very simply constructed arrangement which may be formed as an attachment to 30 already existing pan greasing machines and the like wherein a pump mechanism is provided for conducting a supply of grease or other substance to the swabs which operate within the pans or other containers. It will be noted that we have 35 made ample provision for adjustment of the stroke of the pump so that the quantity of material supplied to the swabs or other equivalent elements may be easily controlled. In addition, a very simple adjustment has been provided 40 whereby the rate or feed of the grease or other substance may be accurately set and maintained.

constant. Attention is also directed to the feature of the release lever mechanism which is adapted to cooperate with the adjusting means for the purpose of rendering the pump mechanism entirely inactive or ineffective temporarily while the operator is attending to some adjustment on the machine or while he might have to leave it unattended for a few moments. It is believed from the above that the construction, 5 operation and advantages will be readily apparent to one skilled in the art without further explanation. 10

While we have shown and described the preferred embodiment of the invention, it should be understood that we reserve the right to make 15 all such changes in the details of construction and the arrangement and combination of parts as will not depart from the spirit of the invention or the scope of the subjoined claims.

Having thus described the invention we claim: 20

In a pump mechanism, a constantly rotating shaft, a cam device operatively driven by said shaft through reducing gearing, a lever movable by said cam device, a plunger operatively connected with said lever and with the pump mechanism, spring means urging said plunger in one direction, and means for limiting movement of said plunger against the resistance of said 25 spring means comprising a quadrant eccentrically pivotedly mounted with its periphery in abutting engagement to the plunger, means for shifting the position of the quadrant, and means disposable between the plunger and the quadrant for maintaining the former against movement regardless of the position of the latter consisting 30 of a rod equipped with an operating handle, and a tapered arm on said rod interposable between the end of the plunger and the periphery of the quadrant. 35

WILLIAM H. SWARTZ. 40
